STRAND HANDLING APPARATUS

Archie J. Dowd, Plainfield, N. J., assignor to
Western Electric Company, Incorporated, New
York, N. Y., a corporation of New York

Application February 7, 1942, Serial No. 429,929

9 Claims. (Cl. 164—48)

This invention relates to strand handling apparatus, and more particularly to apparatus for cutting accurately predetermined lengths in unlimited sequence from continuous strands of relatively little inherent stiffness.

Various kinds of apparatus are commercially available, constructed and adapted to cut segments of predetermined length in unlimited sequence from continuous strands, such as metal wires, which have sufficient inherent stiffness to support a considerable length of themselves cantilever fashion. In some such apparatus a length of wire is drawn from a supply through an open pair of jaws or other gripping means, followed by suitable measuring and cutting devices for a predetermined distance, whereupon the jaws or other means are actuated to grip and hold the wire while a predetermined length is cut off, in such fashion that a more or less considerable length is left projecting from the gripping means for the drawing means to take hold of at the beginning of the next cycle of operation. This projecting portion of wire is unsupported beyond the gripping device except by its own inherent stiffness, being in effect a cantilever beam. An apparatus of this kind may be further adapted not only to cut lengths of insulated wire, but also, at the same time, to strip the insulation from predetermined portions of each end of each length, to provide connector wires which are used in myriad ways in the construction of electrical devices and apparatus. In apparatus for making connector wires with stripped ends, there may be a considerable length of wire projecting from the wire gripping means, at the end of a cycle, unsupported except by its stiffness.

There are instances also in the electrical arts, especially in the manufacture of apparatus for telephone and radio purposes, where it is desired to cut a relatively limp strand in unlimited sequence into portions of predetermined length. For example, in telephone apparatus, great quantities are used of precut lengths of "sleeving." Sleeving, in this sense, is an empty tube, braided of textile threads, in indefinitely long lengths. Sections of predetermined length are cut from these to be slipped over bare or insulated wire in electrical apparatus to provide original or auxiliary protection where particularly needed, either mechanical or electrical or both. Such sleeving may in some instances be impregnated with waterproofing or insulating material also.

At the present time, when it is highly necessary to conserve the nation's output of machine tools and capacity for producing special manu-

facturing apparatus of any kind, special efforts are being made to widen the adaptability of existing machines and apparatus to enable them to carry out functions not contemplated in their original design and construction, preferably often without more than temporarily affecting their effectiveness for their original function and use.

An object of the present invention is to adapt an existing machine intended to cut and strip relatively rigid connector wires, to make such machine effective to cut predetermined lengths of relatively limp sleeving.

With the above and other objects in view, in a machine having means to draw out from a supply by means of a reciprocating gripping device a predetermined length of a strand or plurality of associated strands and having means to cut off a predetermined portion of the said length, the invention may be embodied by providing further a resiliently yielding support for an uncut portion of the drawn-out length to be driven resiliently back by the gripping device during a part of the reciprocation thereof.

Other objects and features of the invention will appear from the following detailed description taken in connection with the accompanying drawings in which the same reference numerals are applied to identical parts in the several figures and in which

Fig. 1 is a plan view of an apparatus embodying the invention;

Fig. 2 is a view thereof in rear elevation with casing parts broken away;

Fig. 3 is a broken enlarged plan view of the gripper carriage;

Fig. 4 is a section on the line 4—4 of Fig. 3;

Fig. 5 is an end view of the showing of Fig. 3;

Figs. 6 to 12 inclusive are successive stages of the cycle of operation of the strand support;

Fig. 13 is a detached, enlarged and partially sectional plan view of the support; and

Fig. 14 is a section on the line 14—14 of Fig. 13.

The apparatus herein disclosed and described was originally a commercially available machine designed and constructed to handle a single strand of insulated electrical conductor wire to cut from a continuous unlimited length thereof, in unlimited sequence, segments all of the same adjustably predetermined length and at the same time to strip away the insulation from a portion of each segment at each end thereof. In accordance with the present invention and as herein further disclosed and described, the apparatus is altered and modified to be capable of handling one or a plurality of strands simultaneously of sleev-

ing or other analogous, relatively limp strands, to cut from a continuous unlimited length of such, in unlimited sequence, segments all of the same adjustably predetermined length.

For a clear understanding of the nature, purpose and scope of the present invention, it will be necessary to describe so much of the original structure and function of the machine disclosed as is required to explain and define the subtractions, additions and alterations which together constitute the embodiment of the present invention. Since, however, the machine generally is the environment of the present invention rather than the invention proper, all details shown for completeness on the drawing need not be fully described in detail in this description and vice versa.

A carriage unit, generally indicated at 20, is reciprocable along a horizontal rail 21 supported in brackets carried on the main frame of the machine. A square shaft 22 is journaled in the brackets to lie parallel to and a little in front of the rail 21 and passes through circular apertures 23 in the side walls of the hollow body 24 of the carriage. A pair of intermeshed partial pinions 25 and 26 is mounted in the carriage below the shaft on pivots parallel to the shaft. On a lug integral with each pinion is mounted pivotally one of a pair of strand gripping levers 27 and 28 respectively, formed with complementary gripping jaws 29 and 30 respectively at their lower ends and connected respectively by links 31 and 32 to the carriage body 24. Hence by rotation of the pinions 25 and 26 the jaws 29 and 30 are separated and raised or brought together and lowered, so that in strand gripping position they lie considerably lower than when widely separated.

A generally cylindrical sleeve 33 is located within in the carriage body 24, and has a central, square bore which receives the square shaft 22, so that the sleeve is slidable on but rotatable by the shaft. The sleeve is journaled in the apertures 23 in the body 24 to be enforcedly reciprocable with the body and freely rotatable therein. Twin levers 34, 34 extending from the sleeve 33 are pivotally attached to a link 35 therebetween, to the outer end of which is rigidly secured one end of a stiff spring member 36, attached rigidly at its other end to a link 37. The link 37 is pivotally secured between twin triangular links 38, 38, which in turn are pivotably supported on a shaft 39, which is journaled in the body 24 and also carries the pinion 26 rigidly secured on its outer end. Between the links 38, twin levers 40, 40 are rigidly secured on the shaft 39, and are attached to the links 38 by a screw threaded adjustable-length link 41, entering pivots 42 and 43 joining respectively the two links 38 with each other and the two levers 40 with each other. A safety link 44 connects the pivot of the levers 34 and link 35 directly to the pivot of the link 37 and links 38, but with so much intentionally provided lost motion and looseness on the pivots that it is never operative unless the spring member 36 is accidentally broken, when the safety link prevents the thus freed elements from running wild.

No matter where the carriage 20 may be on the slide 21, the shaft 22 is effective, if rotated, to turn the levers 34, move the link 35, spring 36 and link 37, turn the links 38 on the shaft 39, move the link 41 and thus turn the levers 40 to turn the shaft 39. The shaft 39 then turns the pinion 26 and so the pinion 25 to open and raise, or lower and close the jaws 29 and 30.

The carriage 20 has a pull and push actuating

rod 45 attached to the right side thereof and running generally parallel to the slide 21 through a support on the outer end of the slide, being freely slideable in the support. To this rod is adjustably and pivotably attached one end of a lever-link, 46, movably fulcrumed at 47 on one arm of a bell crank lever 48 which is itself pivoted at 49 on a bracket of the main frame. Intermediate its extremities the link-lever 46 has an alternative fulcrum at 49 on a link 50 whose other end is pivotally attached to a block 51 slidably adjustable on an arcuate lever 52, pivoted at 53 on a stationary frame bracket. The lever 52 also has a cam roller 54 driven by a cam 55 secured to a vertical drive shaft 56. The cam 55 driving the lever 52 causes the block 51 and link 50 to turn the lever 46 on the fulcrum 47 to shift the carriage along its rail.

The bell crank lever 48 is connected by a link 57 to one end of a lever 58 pivoted at 59 on a stationary frame member and having a cam follower 59 on its other end driven by a cam track 61 in a cam 60 on the shaft 56. The cam 60 driving the lever 58 and link 57 causes the crank 48 to turn the lever 46 on the fulcrum 49 to shift the carriage along its rail.

The cam 60 also has a cam track 62 which drives a follower 63 on a lever 64, pivoted at 62 also, to actuate a pull and push actuating rod 65 to open and close shearing blades 66 and 67, mounted on members driven toward and from each other by twin racks 68 and 68 and a pinion 69, driven by the rod 65. The shear blades 66 and 67 and the parts which support and guide these as well as the parts which support and guide the racks 68 and 68 which are respectively connected to and drive the shear blades 66 and 67, are not shown or described in detail in order not to confuse the drawings with unnecessary detail. The rod 65 pushes and pulls the rack 68 secured to it to pull or push the blade 67. The rack 68 drives the pinion 69, which is pivoted on a stationary pin 63 and which drives the rack 68 to pull or push the blade 66. Guideways for the reciprocating parts 68, 68, 66 and 67 are not believed to require detailed illustration or description.

A further cam 70 on the shaft 56 drives a follower 71 on a lever 72, also pivoted at 92 and which is connected to a link 73 which actuates through levers 74 and 75 a rod 76 to actuate a crank 77 on the square shaft 22 to rotate the same to close or open the jaws 29 and 30.

The shaft 56 is driven through suitable pulleys, belts and gearing as shown from a motor 78. The shaft 56 may also be turned by hand, when adjustments are to be made, by a hand wheel 79.

The various cams, levers, links, cranks, and other actuating and actuated elements above described are so proportioned and adapted and related to each other that when the shaft 56 is driven by the motor 78 at constant speed the hereinafter described cycle of operations is repeated over and over.

Turning now to Figs. 6 to 12 inclusive, let it be assumed that the jaws 29 and 30 have gripped and drawn out to the right, past the cutting plane of the shear knives 66 and 67, the desired predetermined length of a bundle of sleeveing strands 19, here shown as three in number but which may be of any number within the capacity of the jaws to grasp and hold securely. Let it be further supposed that the shear knives have just closed and cut off the predetermined length of the bundle of strands. The jaws still closed then

move a short distance still further to the right. This is a useless but harmless motion for the purposes of the machine as adapted by the present invention. Originally there were auxiliary knives on either side of the shear knives 66 and 67 which were set to cut through the insulation but not the wire core of an insulated wire. The motion of the jaws just described would then strip the insulation from the rear end of the piece or segment of wire just cut. As modified, the stripper knives have been removed from the machine and this action of the jaws, shown in Fig. 7, is waste motion.

At the next stage (Fig. 8), the jaws have opened and dropped the cut off bundle of lengths into any suitable receptacle not shown. The jaws then move to the left, still open and raised above the level of the knives, to the position shown in Fig. 9. They then drop down and close, gripping the bundle of strands again near their new forward ends, as shown in Fig. 10. In this position the jaws are just to the left of the originally present left hand pair of stripper knives, not shown here because they have been removed for the purposes of the present invention. The jaws next move a short distance to left to the position shown in Fig. 11. In the original machine, this served to strip the front end of a strand gripped in the jaws. For present purposes, this motion is idle.

In the next stage, the shear knives 66 and 67 are drawn apart, as shown in Fig. 12. The jaws gripping the bundle of strands then move forward between the opened knives to the position of Fig. 6, the knives close, cutting off the predetermined, desired length, and the operating cycle is completed.

So long as the strands 19 are inherently stiff enough to support themselves, from some point to the left of the position of the knives in Figs. 11 and 12, no modification of the machine is required, beyond removal of the stripper knives to effect the desired results. But when the strands are relatively limp, e. g., are sleeving, after the cut is made in Fig. 6, and the strands are unsupported from some point at least as far from the cutting plane as the left side of the jaws in Fig. 12, the unsupported strand ends will sag and lop down in such fashion that the jaws in Figs. 9 and 10 fail to catch hold of them either properly or at all.

To obviate this, and as a principal feature of the present invention, the device shown in enlarged detail in Figs. 13 and 14, as well as diagrammatically and on a smaller scale in Figs. 6 to 12 inclusive, is introduced. In this a supporting sleeve or tube 80 is located around the path of the strands 19 as they approach the cutting plane of the knives 66 and 67. The tube is supported in a housing 81 secured to a bracket on the machine frame. The tube is slidable in the housing along the strand path and is yieldingly held toward the knives by a spring 82. On the right hand end of the tube is secured a head 83 having a bore 84 coaxial with the bore of the tube. A transversely disposed bore 85 in the head houses in one counterbored end a cylindrical disk 86 having a knurled head 87 outside the head 83, and in the other counterbored end a disk 88 having a peripheral groove therein to receive the end of a jam screw 89 mounted in the head 83. An eccentric cross bar 90 connects the two disks rigidly, and can be turned by loosening the screw 89 and turning the head 87 to narrow the passageway of the strands as desired, and thus effect

a more or less severe frictional grip on the strands passing through, so that when the tension created in the strands, by drawing out a length of them, is suddenly released by the knives, the fresh cut strands ends will not whip back into the tube.

The whole of this device is so located, as shown in Figs. 9 and 10, that when the jaws 29 and 30 move down and close to grip the fresh cut ends of the strand, they just clear the front face of the head 83. Then when the jaws move left as in Figs. 11 and 12, making the now idle stripping movement, the tube 80 yields against the spring 82, and returns again as in Fig. 6 at the next step. Thus the strands are supported to the rightmost possible extent at all times and particularly during the stages shown in Figs. 9 and 10, thus ensuring that the strands will be satisfactorily gripped by the jaws at each operative cycle.

The embodiment of the invention disclosed may 20 obviously be modified as to details of structure without departing from the scope and spirit of the invention as pointed out in the appended claims.

What is claimed is:

25 1. In an apparatus having a reciprocating gripping device to grip and draw out a predetermined length of strand from a supply thereof and shear means to cut off a predetermined portion of the said length, means to support the remaining portion of the said length comprising a supporting member for the said remaining portion of strand, and resilient mounting means for the member arranged so that the gripping device will displace the supporting member resiliently 35 from its normal position during a part of the reciprocating motion of the device.

2. In an apparatus having a reciprocating gripping device to grip and draw out a predetermined length of strand from a supply thereof and shear means to cut off a predetermined portion of the said length, means to support the remaining portion of the said length comprising a supporting member for the said remaining portion of strand, and resilient mounting means for 40 the member arranged so that the gripping device will displace the supporting member resiliently from its normal position during a part of the reciprocating motion of the device, the supporting member being normally closely adjacent to 45 the gripping device when the latter is acting to grip the strand.

3. In an apparatus having a reciprocating gripping device to grip and draw out a predetermined length of strand from a supply thereof and shear means to cut off a predetermined portion of the said length, means to support the remaining portion of the said length comprising a supporting member for the said remaining portion of strand, a guide on which the member is 50 mounted to be slidable to and fro along the strand, and a spring to hold the member yieldably in a normal position on the guide so that the gripping device will displace the member resiliently from the normal position thereof during 55 a part of the reciprocating motion of the device.

4. In an apparatus having a reciprocating gripping device to grip and draw out a predetermined length of strand from a supply thereof and shear means to cut off a predetermined portion of the said length, means to support the remaining portion of the said length comprising a supporting member for the said remaining portion of strand, a guide on which the member is mounted to be slidable to and fro along the strand, and a spring to hold the member yield- 70 75

ably in a normal position on the guide so that the gripping device will displace the member resiliently from the normal position thereof during a part of the reciprocatory motion of the device, the supporting member being normally closely adjacent to the gripping device when the latter is acting to grip the strand.

5. In an apparatus having a reciprocating gripping device to grip and draw out a predetermined length of strand from a supply thereof and shear means to cut off a predetermined portion of the said length, means to support the remaining portion of the said length comprising a tube to enclose and support the said remaining portion of strand, a housing in which the tube is supported to be slidable therein to and fro along the strand, and a spring to hold the tube yieldably in a normal position in the housing so that the gripping device will displace the tube resiliently from the normal position thereof during a part of the reciprocatory motion of the device.

6. In an apparatus having a reciprocating gripping device to grip and draw out a predetermined length of strand from a supply thereof and shear means to cut off a predetermined portion of the said length, means to support the remaining portion of the said length comprising a tube to enclose and support the said remaining portion of strand, a housing in which the tube is supported to be slidable therein to and fro along the strand, and a spring to hold the tube yieldably in a normal position in the housing so that the gripping device will displace the tube resiliently from the normal position thereof during a part of the reciprocatory motion of the device, the tube having one end normally closed adjacent to the gripping device when the latter is acting to grip the strand.

7. In an apparatus having a reciprocating gripping device to grip and draw out a predetermined length of strand from a supply thereof and shear means to cut off a predetermined portion of the said length, means to support the remaining portion of the said length comprising a supporting member for the said remaining por-

tion of the strand, a guide on which the member is mounted to be slidable to and fro along the strand, and a spring to hold the member yieldably in a normal position on the guide so that the gripping device will displace the member resiliently from the normal position thereof during a part of the reciprocatory motion of the device, in combination with means on the member to maintain a frictionally yielding grasp on the strand.

10 8. In an apparatus having a reciprocating gripping device to grip and draw out a predetermined length of strand from a supply thereof and shear means to cut off a predetermined portion of the said length, means to support the remaining portion of the said length comprising a tube to enclose and support the said remaining portion of strand, a housing in which the tube is supported to be slidable therein to and fro along the strand, and a spring to hold the tube yieldably in a normal position in the housing so that the gripping device will displace the tube resiliently from the normal position thereof during a part of the reciprocatory motion of the device, in combination with means on the tube to maintain a frictionally yielding grasp on the strand.

15 9. In an apparatus having a reciprocating gripping device to grip and draw out a predetermined length of strand from a supply thereof and shear means to cut off a predetermined portion of the said length, means to support the remaining portion of the said length comprising a tube to enclose and support the said remaining portion of strand, a housing in which the tube is supported to be slidable therein to and fro along the strand, and a spring to hold the tube yieldably in a normal position in the housing so that the gripping device will displace the tube resiliently from the normal position thereof during a part of the reciprocatory motion of the device, in combination with adjustable means on the tube to maintain an adjustably severe frictionally yielding grasp on the strand.

30 35 40 45 ARCHIE J. DOWD.
